UNITED STATES PATENT OFFICE.

ROBERT SIMON, OF WEEHAWKEN, NEW JERSEY.

METHOD OF MAKING FILLING OR TRAM FOR SILK FABRICS.

SPECIFICATION forming part of Letters Patent No. 358,489, dated March 1, 1867.

Application filed March 21, 1885. Serial No. 159,627. (No model.)

To all whom it may concern:

Be it known that I, ROBERT SIMON, a resident of Weehawken, in the county of Hudson and State of New Jersey, have invented an Improved Method of Making Filling or Tram for Silk Fabrics, of which the following is a full, clear, and exact description, reference being made to the accompanying drawings, in which—

10 Figure 1 is a plan view of my improved silk fabric. Fig. 2 is an enlarged cross-section of a raw-silk thread as used therein. Fig. 3 is an enlarged side view of the tram used in the fabric.

15 This invention relates to a new method of making a filling or tram for silk fabric, in which the shuttle-threads are each composed of a series of tram-threads that lie substantially parallel to one another in the weft.

20 I proceed in the following manner to make a shuttle thread or filling for my fabric: First, a series of cocoon-threads, *a a*, Fig. 2, are united by their natural gum and formed into a raw-silk thread, *b*. Of such raw-silk threads two

or more are then doubled and twisted together, thus forming a tram-thread, *d*, and a series of these tram-threads *d d*, thus produced, are doubled again and twisted; but, after dyeing, the second twist is taken out of them, leaving the whole filling *A* composed of a series of tram-threads, *d*, that lie substantially parallel to one another, as in Fig. 3.

In producing a silk fabric with my improved tram *A* therein, I interlock the warp-threads *e* with the compound tram-threads *A* by means of the ordinary mechanism.

What I claim is—

The method herein described of preparing filling for silk fabrics, consisting in doubling and twisting a number of raw-silk threads to form tram-threads, doubling and twisting a number of these tram-threads, dyeing the same, and then taking out the second twist, substantially as described.

ROB. SIMON.
